Primary Examiner—Doris V. Coles*Assistant Examiner*—Catherine R. Oliver*Attorney, Agent, or Firm*—Renner, Kenner, Greive, Bobak,
Taylor & Weber[57] **CLAIM**

The ornamental design for a ball holder, as shown and described.

DESCRIPTION

FIG. 1 is a front elevational view of a ball holder showing my new design;

FIG. 2 is a top view thereof;

FIG. 3 is a side elevational view of a ball holder, the opposite side elevational view being a mirror image thereof;

FIG. 4 is a bottom view thereof, with the bottom being the same for each embodiment;

FIG. 5 is a rear elevational view thereof;

FIG. 6 is a front elevational view of a second embodiment thereof;

FIG. 7 is a top view thereof;

FIG. 8 is a rear elevational view thereof;

FIG. 9 is a front elevational view of a third embodiment thereof;

FIG. 10 is a top view thereof;

FIG. 11 is a rear elevational view thereof;

FIG. 12 is a front elevational view of a fourth embodiment thereof;

FIG. 13 is a top view thereof;

FIG. 14 is a rear elevational view thereof; and,

FIG. 15 is a side elevational view, with the side being the same for each embodiment and the opposite sides being a mirror image thereof.

The broken lines showing at least one ball in FIGS. 1 and 3, respectively, are environmental only and form no part of the claimed design.
